UNITED STATES PATENT OFFICE.

EDMUND W. FARRIS, OF FARGO, NORTH DAKOTA.

INTERNAL-COMBUSTION ENGINE.

Application filed June 29, 1920. Serial No. 392,621.

To all whom it may concern:

Be it known that I, EDMUND W. FARRIS, citizen of the United States, residing at Fargo, in the county of Cass and State of North Dakota, have invented certain new and useful Improvements in Internal-Combustion Engines, of which the following is a specification.

This invention relates to improvements in internal combustion engines and more particularly to the lubricating means therefor.

The invention forming the subject matter of this application aims to provide a lubricating system for internal combustion engines having novel means for supplying an increased quantity of oil to the several working parts when the vehicle propelled by the engine is ascending a hill.

A further object of the invention is to provide a lubricating system for internal combustion engines having means for automatically decreasing the supply of oil to the several working parts of the same when the vehicle propelled by the engine is descending a hill.

A further object of the invention is to provide a lubricating system for internal combustion engines which may be incorporated in the engine while the same is being built or at any time thereafter without materially altering the construction of the engine.

A further object of the invention is to provide a lubricating system for internal combustion engines having efficient means for collecting grit and other sediment which may be in the oil so that such grit or sediment is prevented from working into the bearings and other working parts.

A further object of the invention is to provide a lubricating system for internal combustion engines which is entirely automatic in its operation, efficient and durable.

Other objects and advantages of the invention will be apparent during the course of the following description.

In the accompanying drawings forming a part of this application and in which like numerals are employed to designate like parts throughout the same,

Figure 1 is a side elevation of an internal combustion engine having the improved lubricating system applied thereto, parts of the engine being shown in section to more clearly illustrate the application of the lubricating system,

Figure 2 is a detail longitudinal section through an internal combustion engine having the improved oil regulator applied thereto, the view illustrating the position of the engine and automatic operation of the oil regulator when the vehicle to which the engine is attached is ascending a hill,

Figure 3 is a similar view, the view illustrating the position of the various parts when the vehicle to which the engine is attached is descending a hill,

Figure 4 is a perspective of the improved oil regulator,

Figure 5 is a detail section through the improved oil regulator,

Figure 6 is an end elevation of the oil regulator,

Figure 7 is a perspective of an oil pan embodied in the invention, and

Figure 8 is a plan view of the oil pan,

Figure 9 is a detail view of an engine and the supporting means therefor, parts thereof being shown in section,

Figure 10 is a vertical transverse section taken on line 10—10 of Figure 9,

Figure 11 is a fragmentary perspective of the crank case of an internal combustion engine and a leveling member for the motor.

The invention forming the subject matter of this application is especially adapted for use in connection with Ford motors though it is obvious that the inventive idea may be carried out in motors of other types. However, in the Ford motor, the principal objection to the lubricating system is the fact that no means is provided for increasing the supply of oil when the motor is propelling a vehicle uphill and, therefore, the bearings in the forward portion of the motor soon become worn.

On the other hand, when the forward portion of the motor is inclined upwardly due to the ascension of the vehicle, the oil in the forward portion of the motor gravitates to the rear of the motor, thereby leaving the forward bearings without the proper supply of oil. This invention overcomes the above difficulty since it automatically increases the supply of oil to the forward portion of the crank case when the vehicle is ascending a hill and also since it conveys the oil rearwardly without lubricating the forward bearings when the motor is descending a hill thereby preventing the forward cylinders from fouling due to an excessive supply of oil.

In the drawings, wherein for the pur-

pose of illustration is shown a preferred embodiment of the invention, the numeral 10 generally designates an internal combustion engine composed, as usual, of a crank case 5 11 upon which is mounted a plurality of cylinders 12. For the purpose of clearness, the usual longitudinally extending crank shaft and the piston rods connected thereto have been omitted though it is obvious that 10 the lower portions of the connecting rods dip into troughs 14 arranged in spaced relation in an oil pan 15 detachably connected to the crank case through the medium of a plurality of bolts 16. The flywheel case 15 18 at the rear of the motor receives a quantity of oil 20 which is elevated by a flywheel 22 and discharged into the inlet end or neck 24 of an oil conveying pipe 26. The oil conveying pipe is arranged within the 20 crank case and conveys the oil to the forward portion of the motor where a V-shaped oil receptacle 28 is arranged. The oil conveying pipe 26 is, of course, inclined downwardly towards its forward end so that the 25 oil upon entering the neck 24 is conveyed forwardly and discharged into the oil receptacle 28 which is arranged directly beneath the discharge end of the pipe 26. The oil receptacle 28 may, if desired, be provided 30 with a pair of laterally presented apertured ears 30 by means of which the receptacle may be rigidly secured to the side of the motor, though it is obvious that other suitable means may be employed without departing from the spirit of the invention. 35

As illustrated particularly in Figure 5, the oil receptacle 28 is provided with a transversely extending partition 32 which forms an oil discharge passage 33 within the receptacle. The discharge passage 33 is formed in the rear portion of the receptacle 28 by the partition 32 having its free end portion extended downwardly as indicated at 35; and discharging the oil into the forward trough 14 of the oil pan. The upper end of the partition 32, of course, terminates below the upper side of the receptacle 28 so that oil will flow from the receptacle into the passage 33 without the possibility of flowing over the sides of the receptacle.

As further illustrated in Figure 5, the receptacle 28 is provided with a second transverse partition 37 which forms a second oil discharge passage 38 having communication with a rearwardly extending oil conveyer in the form of a pipe 40. The pipe 40 is inclined downwardly toward its free end 60 and discharges into the rearmost trough 14 when the receptacle is so positioned to supply oil to the forward oil passage 33.

When the motor is in operation and the vehicle on which the same is mounted is running on level ground, the oil is conveyed by

the flywheel to the neck 24 of the oil conveyer 26 and from the oil conveyer 26 into the receptacle 28. With the motor positioned as above described, the oil within the receptacle 28 flows over the upper end of the partition 32 and into the oil discharge passage 33 and then through the discharge pipe 34 into the forward oil trough of the crank case. In this manner a proper supply of oil is assured to the forward and in fact all of the connecting rod and main bearings. Upon leaving the forward trough 14 of the oil pan, the oil gradually moves rearwardly until it enters the oil reservoir at the bottom of the flywheel case 18.

When the vehicle is ascending a hill, the motor is of course, inclined rearwardly with the result that an increased supply of oil to the forward bearings of the motor is provided. This is accounted for by the fact that the oil in an increased quantity flows over the upper end of the partition 32 and through the discharge passage 33 and the pipe 34 into the forward trough. Therefore, the supply of oil to the forward bearings is automatically increased when the strain on the motor is increased.

When the vehicle is descending a hill, the motor is, of course, inclined downwardly toward its forward end with the result that the oil is caused to flow into the forward oil discharge passage 38 and through the rearwardly extending passage 40 to the rear trough. With the motor thus positioned, the oil is conveyed from the receptacle 28 to the rear of the motor so that the oil is not allowed to accumulate in excessive quantities in the forward portion of the engine and thereby cause the forward cylinders to foul.

When the motor is arranged horizontally and is in operation, the oil is fed to the forward trough by reason of the fact that the rear partition 32 terminates below the horizontal plane of the forward partition 37. The receptacle 28 and pipes 34 and 40 may be applied to an internal combustion engine either during the construction of the latter or after the motor has been in use.

As illustrated in Figures 7 and 8, the oil pan which forms a part of the crank case is provided with a plurality of transversely extending U-shaped baffles 50 arranged rearwardly of the transversely extending troughs 14 and having forwardly extending side arms 51 which are tapered toward their forward ends and serve as a means for collecting the oil as the same flows rearwardly from the forward portion of the motor. More particularly, when the motor is propelling a vehicle uphill, the motor is, of course, inclined rearwardly to a slight extent and therefore the oil is caused to flow into the reservoir at the rear of the

motor. As set forth above, it is objectionable to allow the oil to flow entirely to the rear of the motor when the motor is under an increased strain and, therefore, the forwardly extending side arms 51 of the baffles 50 serve as a means for confining the oil in the several transversely extending troughs when the motor is inclined rearwardly and in operation.

10 The oil pan is also provided with a plurality of U-shaped baffles 54 arranged forwardly of the several troughs 14 and provided with rearwardly extending arms 56 which, as clearly illustrated in Figure 7, 15 are arranged inwardly of and in spaced relation to the terminal portions of the side arms 51 so as to provide an oil passage between the adjacent portions of the arms 51 and 56. The oil passages thus formed between the arms 51 and 56 allow the oil upon flowing rearwardly to enter the troughs 14 and thereby be trapped by the baffles 50.

When the motor is inclined downwardly toward its forward end as the result of the 25 vehicle descending a hill, the natural tendency is under ordinary circumstances for the oil to flow to the forward portion of the crank case and thereby cause the forward cylinder or cylinders to foul. However, the 30 baffles 54 with the rearwardly extending arms 56 serve as an efficient means for preventing the oil from flowing to the forward portion of the motor in excessive quantities. The baffles 50 and 54 may be formed integral with the oil pan during the manufacture and if desired the intermediate baffles may have their connecting portions formed from one piece as illustrated.

The improved oil regulator operates most 40 efficiently on a level motor and as the forward portion of a Ford motor is in some cases lower than the rear portion of the motor when mounted on a frame I have provided a simple means whereby the forward portion of the motor may be elevated 45 without altering the construction of any of the parts. As illustrated in Figure 9, the forward portion 60 of the crank case 11 is provided with a collar 62 which rotatably 50 receives the shaft of a hand crank 64. Under ordinary conditions and as the motor is now mounted upon the frame, the collar 62 rests within a semi-circular recess 66 in a head block 68 which latter is mounted upon the cross spring 70 and secured to the same through the medium of U-shaped bolts 72. The forward portion of the crank case may be slightly elevated by arranging a semi-circular bearing 74 in the semi-circular recess 66 directly beneath the collar 62. A cap 76 of semi-circular formation is extended over the collar 62 and is provided with apertured ears 78 alined with the apertured ears 80 of the bearing 74 for the retention of cap bolts 82 having threaded en-

gagement with the head block 68. The application of the semi-circular bearing member 74 elevates the forward portion of the motor so that the same is positioned horizontally. The semi-circular bearing may be of a thickness sufficient to level the motor and may be applied without any elaborate dismantling of the motor.

With reference to the foregoing description, taken in connection with the accompanying drawings, it will be observed that an internal combustion engine having the improved lubricating system will operate with an increased degree of efficiency since an increased supply of oil is provided when the motor is under strain and since the supply of oil is automatically decreased when the strain on the motor is removed. Attention is invited to the fact that any sediment which may be in the oil will remain in the lower portion of the receptacle 28 and will not be allowed to flow either through the forward passage 38 or the rearward passage 33.

It is to be understood that the form of the invention herewith shown and described is to be taken as a preferred example of the same and that such minor changes in arrangement and construction of parts may be made as will remain within the spirit of the invention and the scope of what is claimed.

Having thus described the invention, what is claimed as new is:

1. The combination with an internal combustion engine having means for discharging oil at the forward portion of the same, of an oil receiving member arranged at the forward portion of the crank case of the engine and provided with discharge passages, and oil conveyers having communication with said passages and extending in opposite directions from the receptacle.

2. The combination with an internal combustion engine having a crank case, of an oil receiving receptacle arranged in said crank case and provided with a pair of partitions thereby forming a pair of passages, and pipes extending forwardly and rearwardly from said receptacle and having communication with said passages.

3. The combination with an internal combustion engine provided with a crank case, of an oil receiving receptacle arranged within said crank case and provided with forward and rearward partitions thereby forming forward and rearward passages, said partitions terminating below the horizontal top edge of said receptacle, a rearwardly extending pipe having communication with said forward passage, and a forwardly extending pipe having communication with said rearward passage.

In testimony whereof I affix my signature.

EDMUND W. FARRIS. [L.s.]
